MANUFACTURE OF MOTOR FUEL

Francis Horton, Riverdale, N. Y., Lebbeus C. Kemp, Port Arthur, Tex., and Richard E. Nagle, New York, and Loren F. Scoville, White Plains, N. Y., assignors, by mesne assignments, to The Texas Company, New York, N. Y., a corporation of Delaware

Application June 20, 1939, Serial No. 280,064

12 Claims. (Cl. 260—683.4)

This invention relates to the manufacture of motor fuel and has to do particularly with the alkylation of isoparaffins with olefins to produce high antiknock branch chain paraffin hydrocarbons of gasoline boiling range. The invention is concerned with the conversion of normally gaseous hydrocarbons into high antiknock gasoline hydrocarbons by the alkylation of low-boiling isoparaffins, such as isobutane or isopentane, with olefins in the presence of an alkylation catalyst. The invention contemplates a process for the commercial production of high antiknock motor fuel, for example aviation gasoline, from refinery gases including cracking still gases.

In the alkylation of isobutane with olefins, it is desirable to treat an unsaturated hydrocarbon mixture containing isobutane in excess of the olefins. Refinery gases such as cracking still gases generally contain an excess of olefins and special methods for obtaining a suitable charge for alkylation are necessary. A phase of the invention includes the preparation of a suitable charge to the alkylation operation.

In the preparation of the charging stock, cracking still gases or other refinery gases or mixtures thereof, are fractionated to obtain a charge suitable for alkylation with or without the addition of additional low-boiling isoparaffins from another source. For example, gases derived from a cracking still may be fractionated to remove lighter and heavier constituents and the remains intermediate cut used as the charge. Thus, by removing propane on the low side and normal butane and heavier on the high side, a middle cut may be obtained of the desired characteristics. Such an intermediate cut may comprise a fractionator or stabilizer side stream which on fractionation or debutanization produces a satisfactory charge for alkylation. In case the side stream has a fairly wide boiling range, showing only rough fractionation, then the side stream may be fractionated to obtain a rather sharply fractionated cut, and this cut used as such, or after debutanization to separate a portion of the normal butane.

It is desirable when using a stabilizer side stream to enrich such stream, preferably after further fractionation, with an extraneous light condensate containing constituents similar to those in the side stream, to adjust the proportion of isobutane and olefins and at the same time increase the volume of available charge. Such extraneous light condensate may be an overhead fraction from a fractionator or stabilizer, gases from an accumulator drum of a cracking still, or

an absorption condensate obtained by absorption extraction of various cracking still gases. The light condensate is preferably depropanized prior to mixing thereof with the side stream.

5 The mixture of side stream and light condensate is preferably debutanized, prior to charging the mixture to the alkylation operation. The debutanizing operation removes all or a portion of the normal butane and thereby increases the ratio of isobutane to olefins. By regulating the respective proportions of the side stream and the light condensate, a product containing the desired ratio of isobutane to olefins for alkylation is readily secured. It is preferable that the charge contain a ratio of isobutane to olefins of at least 1:1 and preferably a considerable excess of isobutane, for example a ratio of isobutane to olefins within the range of about 2:1 and 7:1, or higher.

10 Another feature of the invention is an improved type of alkylation operation. In the alkylation operation a stream of isobutane and catalyst may be circulated through a mixer, a chiller, a reaction zone, and back to the mixer. The hydrocarbon charge containing the isobutane and olefins is injected into this stream. Fresh catalyst may be added to the stream and spent catalyst withdrawn. In the reaction zone the isobutane is alkylated by the olefins in an exothermic reaction, and the exothermic heat of reaction is 15 removed in the chiller by refrigeration with a suitable refrigerant, such as propane.

20 Another feature of the invention is the treatment or distillation of the hydrocarbon alkylation products. The crude alkylate is fractionated to remove excess or residual normally gaseous hydrocarbons which are recycled, at least in part, to the charge fractionation operation. It is preferable to debutanize the crude alkylate and fractionate at least a portion of the overhead cut to 25 separate a fraction rich in isobutane which may be recycled to the alkylation operation. The remainder containing normal butane may be returned to the fractionation operation in which the charge is fractionated for depropanization.

30 A preferred method of operation is to split the overhead from the debutanizer, returning one portion to the charge fractionator and further fractionating the other portion to concentrate the isobutane for recycling to the alkylation operation. The normal butane which is separated in the fractionation of the latter portion may be discharged from the system and the normal butane so discharged may be so regulated as to be approximately equal to the normal butane entering the system in the fresh feed. In this way

a balanced operation is obtained whereby an excessive volume of butane will not build up in the system.

The invention will be more fully understood from the following description read in connection with the accompanying drawing which shows a diagrammatic sketch of one form of apparatus for carrying out the process of the invention.

Referring to the drawing, a cracked naphtha, for example from an accumulator drum of an adjacent cracking still, is passed through a line 1 to a stabilizer 2. In this stabilizer a stabilized naphtha is produced which is withdrawn from the bottom thereof through the line 3. A light hydrocarbon fraction containing all or a portion of the C₃ hydrocarbons, including propane, is taken overhead through the line 5. A side stream containing C₄ hydrocarbons, with or without any portion of the C₃ hydrocarbons, is withdrawn through the line 6. Such a side stream may be relatively high in isobutane content and contain isobutane in considerable excess of the olefins. The side stream is forced by the pump 7 through the line 8 to a fractionator 10. In the fractionator the lighter hydrocarbons, such as all or a portion of the C₃ hydrocarbons are removed overhead through the line 11. The light fractions taken overhead from the stabilizer 2 through the line 5 and from the fractionator 10 through the line 11, are joined and passed through the line 12 and a condenser 14, wherein the hydrocarbons are at least partially condensed, and the resulting condensate collected in receiver 15. The uncondensed hydrocarbons are removed from the top of the accumulator through the line 16. The condensate in the accumulator 15, including propane, is withdrawn from the bottom thereof through the line 18 and pumped by the pump 19 through the line 20 to the upper portion of the fractionator 10, and through the line 21 to the upper portion of the stabilizer 2, as a reflux medium. The liquid fraction in the fractionator 10, preferably a C₄ fraction, is withdrawn from the bottom of the fractionator 10 through the line 22 and pumped by the pump 23 or sent under fractionator pressure without a pump through the line 24 to a debutanizer 25, or may be used direct as alkylation charge by passing it through branch line 26.

A light condensate, such as the lower boiling fractions of a debutanized cracked naphtha, or debutanized absorption condensate, preferably containing C₄ hydrocarbons and a considerable amount of hydrocarbons boiling somewhat above C₄ and containing isobutane and butylenes in which the butylenes are ordinarily in excess of the isobutane, may be charged through the line 27 and commingled in the line 22 with the C₄ cut withdrawn from the bottom of the fractionator 10. This light condensate in mixture with the C₄ cut is passed to a debutanizer 25. In the debutanizer 25, a debutanized light naphtha, preferably containing at least a portion of the normal butane, is withdrawn from the bottom of the debutanizer through the line 28. A C₄ fraction containing isobutane in excess of the olefins is removed overhead from the debutanizer through the line 29 and condenser 30. In the condenser the hydrocarbons are liquefied and the condensate forced by the pump 31 to the manifold line 32, communicating with branch lines 33, 34 and 45 whereby the hydrocarbon charge may be split and passed in multiple injection into alkylation stages 1, 2 and 3 respectively. A portion of the condensate in line 32 may be

returned to the upper portion of debutanizer 25 as a reflux.

The alkylation stages 1, 2 and 3 are multiple units and while three stages are shown, it is to be understood that any number may be used. The details of only stage 1 are shown.

The hydrocarbon charge is passed through branch line 33 to the stage number 1 and is introduced into the line 35 through which is circulated, by the pump 36, a stream of alkylation catalyst, alkylate and isobutane. The mixture is passed through a mixer 37 which may be of any well known or preferred type whereby the hydrocarbons are intimately contacted with the catalyst. The mixture is then passed through the line 38 to a chiller 39 wherein the exothermic heat of reaction is removed by a refrigerating medium passing in indirect contact with the hydrocarbons.

The refrigerating medium is preferably propane which is introduced through the line 40 to a tank 41. The liquid propane is passed from the bottom of the tank 41 through the line 42 into the chiller 39 wherein the propane is vaporized thereby effecting cooling by indirect heat exchange. The vapors pass from the chiller through the vapor line 43 back to the tank 41. The vapors of propane are removed through the line 44 to a compression unit to be compressed, cooled and condensed to form liquid propane which may be recharged to the system through the line 46.

The mixture of catalyst and hydrocarbons passes from the chiller 39 through the line 46 to a reactor 48, wherein additional time is allowed for the alkylation reaction to take place. The reactor may be omitted in case sufficient reaction is secured in the mixer and chiller. The products are withdrawn from the reactor through the line 49 to a settler 50, and any portion of the reaction mixture may be passed through the line 51 controlled by orifice 52 for recycling. In the settler 50 the catalyst is separated from the hydrocarbons and is withdrawn through the line 54 and may be recycled through the line 55. The hydrocarbons are passed from the settler through the line 56 to the stage 2 of the process which is substantially identical with stage 1 and is shown diagrammatically. The hydrocarbons from stage 2 are passed through the line 57 to stage 3. From stage 3 the hydrocarbons are passed through the line 58 to a neutralizer 60, referred to hereinafter.

Fresh catalyst may be introduced into the alkylation stages through the line 67 connecting with branch lines 68, 69 and 70 whereby the fresh catalyst may be introduced into stages 1, 2 and 3 respectively, preferably into the circulating stream of hydrocarbons and catalyst. The spent catalyst may be withdrawn from stages 1, 2 and 3 respectively through the lines 71, 72 and 73, which communicate with a draw-off line 75, for discharging the spent catalyst from the system for recovery or other disposal.

In the alkylation units just described, the circulating streams of hydrocarbon and catalyst contain a ratio of catalyst to hydrocarbon of about 1:1 by volume. The catalyst is preferably sulfuric acid of about 90 to 100% strength, although other suitable liquid catalysts are contemplated, such as hydrated boron trifluoride. A very high ratio of circulated hydrocarbon to fresh hydrocarbon is maintained. The ratio may range between about 5:1 and 100:1 and preferably between about 10:1 and 30:1.

In the neutralizer 60, the hydrocarbons are

contacted with a neutralizing agent, such as dilute caustic soda or soda ash solution, introduced through the line 61 and withdrawn through the line 62. The neutralized hydrocarbons are pumped from the neutralizer 60 through the line 63 by the pump 64 to a debutanizer 65. The overhead from the debutanizer 65, containing isobutane and all or a portion of the normal butane, is passed through line 78 to a condenser 80 wherein the hydrocarbons are substantially condensed. The condensate from the condenser 80 is passed all or in part through the line 81 and recycled by the pump 82 through the line 83 to the fractionator 10. In this way the recycled hydrocarbons are refractionated along with the fresh charge so that the isobutane content thereof eventually reaches the alkylation system for further reaction with olefin; and for increasing the ratio of isoparaffins to olefins. It is evident that this recycle portion of the overhead from debutanizer 65 is thereby subjected to the depropanizing operation in fractionator 10, thereby preventing propane buildup in the system.

It is preferable to withdraw at least a portion of the condensate from the condenser 80 through the branch line 84 and pump 86 to a fractionator 88. In the fractionator 88 separation is made between the isobutane and normal butane. The normal butane fraction is withdrawn as a condensate from the lower portion of the fractionator 88 through the line 90 and discharged from the system or used, if desired, for increasing the volatility of stabilized naphthas, for example the stabilized naphtha withdrawn from the bottom of stabilizer 2. A fraction rich in isobutane is passed from the top of the fractionator 88 through the vapor line 91 to a condenser 92 wherein the hydrocarbons are substantially condensed. The condensate is passed through the line 94 to a pump 95 which recycles the isobutane fraction through the line 96 to the line 33, for charging along with the fresh olefinic charge to the first stage of the alkylation system. The isobutane so recycled increases the amount of available isobutane for alkylation and also aids in creating a considerably higher ratio of isobutane to olefins in the reaction mixture than in the fresh feed to the alkylation system. The amount of hydrocarbons charged through the branch line 84 to the fractionator 88 is preferably regulated whereby the net amount of normal butane discharged from the system through the line 90 is approximately equal to the amount of normal butane entering the system in the fresh feed to the alkylation zone. In this way building up of an excess normal butane in the system is avoided.

The alkylate is withdrawn from the bottom of the debutanizer 65 and passed through the line 88 to a fractionator 100, wherein the alkylate is separated into the desired fractions. An aviation gasoline of approximately 311° F. end point is taken overhead through the vapor line 101 and condenser 102. A side stream of naphtha is withdrawn from an intermediate point of the fractionator 100 through the line 103 to a stripper 104 from which vapors may be returned to the fractionator through vapor line 105. A naphtha of about 300° to 400° F. is withdrawn from the bottom of the stripper through the line 106. The latter naphtha may be used in the manufacture of a heavy aviation or safety fuel. A fraction heavier than gasoline and boiling

above about 400° F. is withdrawn from the bottom of the fractionator through the line 108.

An example will now be given of the operation of the invention although it is to be understood that the invention is not limited to the specific example.

An unstabilized naphtha from a cracking still is charged to a stabilizer from which a stabilized naphtha, an overhead vapor fraction containing C₃ hydrocarbons, and a side stream relatively rich in isobutane, comprising mainly C₄ hydrocarbons with some lighter hydrocarbons, are withdrawn. The side stream contains about 20 parts isobutane, 5.3 parts isobutylene, 3.8 parts butylene-1, 12 parts n-butane, 4.1 parts butylene-2 and the remainder lighter and heavier hydrocarbons. The side stream is passed to a fractionator wherein the lighter hydrocarbons are fractionated out in order to obtain a more concentrated C₄ fraction. The bottoms from the fractionator containing the C₄ fraction are mixed with a depropanized debutanizer overhead, a depropanized absorption condensate, comprising mainly C₄ hydrocarbons, and light naphtha hydrocarbons including pentanes, hexanes and heavier. The depropanized debutanizer overhead shows about 17.9 parts isobutane, 12.9 parts isobutylene, 9.5 parts butylene-1, 36.5 parts n-butane, 17.5 parts butylene-2 and the remainder heavier hydrocarbons. The depropanized absorption condensate contains about 9.6 parts isobutane, 7.3 parts isobutylene, 5.4 parts butylene-1, 22.4 parts n-butane and 10 parts butylene-2 and the remainder heavier hydrocarbons.

The resulting mixture containing about 46 parts of fractionated stabilizer side stream, about 174 parts of depropanized debutanizer overhead, and about 122 parts of depropanized absorption condensate, are charged to a debutanizer. The mixture charged to the debutanizer analyzes about 47.6 parts isobutane, 25.5 parts isobutylene, 18.7 parts butylene-1, 70.9 parts n-butane, 31.6 parts butylene-2 and the remainder mainly heavier hydrocarbons. In the debutanizer a fraction consisting essentially of C₄ hydrocarbons, amounting to about 23% of the charge to the debutanizer, are separated as overhead, and a light naphtha containing a portion of the normal butane is withdrawn as bottoms. The debutanizer overhead contains about 45.2 parts of isobutane, 13.6 parts isobutylene, 9.9 parts butylene-1, 7.1 parts n-butane and 3.2 parts butylene-2. The overhead fraction is condensed and the condensate split into approximately equal portions between three alkylation units connected in series. A recycle stream of isobutane is also charged to the first stage, whereby a ratio of isobutane to olefins in the feeds to each stage is at least 5:1 by volume.

In each alkylation unit the fresh feed is mixed with a stream of recycle hydrocarbons, principally isobutane, alkylate and sulfuric acid catalyst and the mixture passed through a mixer to obtain intimate contact, then through a chiller wherein the heat of reaction is removed by propane refrigeration. The mixture is passed from the chiller to a reaction tank from which the hydrocarbons and catalyst are withdrawn. The stream so withdrawn is split, a portion recycled and the remainder passed to a settler. The ratio of acid to hydrocarbon in the circulating stream is about 1:1 by volume. The ratio of recirculated hydrocarbons to fresh hydrocarbon feed is about 30:1. The acid in the reaction products is maintained at about 90 to 100%

strength; sufficient fresh acid is added to maintain the strength of the acid catalyst at the desired point and an amount of spent acid is withdrawn approximately equal to the amount of the fresh acid added. In the settler the remainder of the acid is separated from the hydrocarbons and may be recycled to the system or sent to the next mixing stage.

The crude alkylate withdrawn from the final settler is neutralized with dilute caustic soda solution and the neutralized hydrocarbons are passed to a debutanizer. An overhead cut from the debutanizer is split into two streams, a portion being returned to the side cut fractionator, referred to heretofore, and the balance going to a butane fractionator. The net normal butane content of the fresh feed is separated in the fractionator and discharged from the system. A recycle stream rich in isobutane taken overhead from the butane fractionator is recycled to the first stage of the alkylation system. The bottoms from the debutanizer are charged to a final fractionator where they are separated by conventional atmospheric distillation into a 311° F. end point overhead, a 311° to 400° F. side cut and bottoms boiling above 400° F. An aviation gasoline of 311° F. end point amounting to approximately 90%, 311° F. to 400° F. naphtha, amounting to about 8%, and bottoms boiling above 400° F. amounting to about 2%, are obtained. The aviation gasoline shows an octane number of about 90, the intermediate naphtha fraction an octane number of about 80.

Obviously many modifications and variations of the invention, as hereinbefore set forth, may be made without departing from the spirit and scope thereof, and therefore only such limitations should be imposed as are indicated in the appended claims.

We claim:

1. A process for the manufacture of anti-knock gasoline, which comprises stabilizing an unstabilized cracked naphtha, separating an overhead stream from the stabilizer containing mainly C₃ and lighter hydrocarbons, separating a side stream from the stabilizer containing C₄ olefins and paraffins and some C₃ hydrocarbons, fractionating said side stream to remove additional C₃ hydrocarbons as well as a portion of normal butane therefrom to provide a fraction concentrated in isobutane and C₄ olefins, subjecting said concentrated isobutane and C₄ olefin fraction to an alkylation operation in an alkylation reaction zone wherein isobutane is alkylated by said olefins, separating an unstabilized alkylate from the reaction products, stabilizing said separated alkylate to separate normally liquid alkylate from an overhead fraction consisting essentially of isobutane and normal butane, together with any C₃ hydrocarbons remaining in the system, recycling a portion of said overhead fraction to the said side stream fractionating operation to prevent buildup of C₃ hydrocarbons in the system, fractionating another portion of said overhead to separate an isobutane fraction from a normal butane fraction, and recycling the said isobutane fraction directly to the said alkylation zone.

2. A process for the manufacture of anti-knock gasoline, which comprises stabilizing an unstabilized cracked naphtha, separating a C₄ hydrocarbon stream from the stabilizer containing butylenes, normal butane, isobutane and some C₃ hydrocarbons, fractionating said stream to remove C₃ hydrocarbons therefrom, debutan-

izing the said fractionated C₄ stream to separate at least a portion of the normal butane, thereby increasing the concentration of the isobutane and butylenes therein, subjecting the debutanized product to alkylation in the presence of an alkylation catalyst whereby isobutane is alkylated by the butylenes to produce gasoline hydrocarbons of high anti-knock value, separating unstabilized alkylate from the reaction products, stabilizing said separated alkylate to remove therefrom a light fraction consisting essentially of isobutane and normal butane together with any C₃ hydrocarbons remaining in the system, and recycling at least a portion of said light fraction to the stabilizer C₄ stream fractionating operation to thereby prevent buildup of C₃ hydrocarbons in the system while maintaining excess isobutane therein.

3. A process for the manufacture of anti-knock gasoline, which comprises stabilizing an unstabilized cracked naphtha, separating a C₄ hydrocarbon stream from the stabilizer containing butylenes, normal butane, isobutane and some C₃ hydrocarbons, fractionating said stream to separate C₃ hydrocarbons therefrom, debutanizing the said fractionated C₄ stream to separate at least a portion of the normal butane thereby increasing the concentration of the isobutane and butylenes therein, subjecting the debutanized product to alkylation in the presence of an alkylation catalyst whereby isobutane is alkylated by the butylenes to produce gasoline hydrocarbons of high anti-knock value, separating normally liquid alkylate from the reaction products, also separating from the reaction products a residual gaseous fraction consisting essentially of isobutane, normal butane and any C₃ hydrocarbons retained in the system, recycling a portion of said residual gaseous fraction to the stabilizer C₄ stream fractionating operation to prevent buildup of C₃ hydrocarbons in the system while returning isobutane thereto, fractionating another portion of said residual gaseous fraction to separate a fraction rich in isobutane from a fraction rich in normal butane, and recycling said fraction rich in isobutane to the alkylation operation to maintain excess isobutane therein while preventing buildup of normal butane in said system.

4. A process for the manufacture of anti-knock gasoline, which comprises stabilizing an unstabilized cracked naphtha, separating a C₄ hydrocarbon stream from the stabilizer containing butylenes, normal butane, isobutane and some C₃ hydrocarbons, fractionating said stream to separate C₃ hydrocarbons therefrom, debutanizing the said fractionated C₄ stream to separate at least a portion of the normal butane thereby increasing the concentration of the isobutane and butylenes therein, subjecting the debutanized product to alkylation in the presence of an alkylation catalyst whereby isobutane is alkylated by the butylenes to produce gasoline hydrocarbons of high anti-knock value, separating normally liquid alkylate from the reaction products, also separating from the reaction products unreacted normally gaseous hydrocarbons consisting essentially of isobutane and normal butane and any C₃ hydrocarbons retained in the system, dividing said unreacted normally gaseous hydrocarbons into separate streams, recycling one stream to the stabilizer C₄ fractionating operation to prevent buildup of C₃ hydrocarbons in the system while returning isobutane thereto, subjecting another stream containing normal bu-

tane in an amount approximating that in the said debutanized product fed to the alkylation operation to fractionation to separate an isobutane-rich fraction from a normal butane fraction, and recycling the isobutane-rich fraction to the alkylation operation to thereby maintain excess isobutane in the system while preventing buildup of normal butane therein.

5. A process for the manufacture of anti-knock gasoline which comprises stabilizing an unstabilized cracked naphtha, separating a C₄ hydrocarbon stream from the stabilizer containing butylenes, normal butane, isobutane and some C₃ hydrocarbons, fractionating said stream to separate C₃ hydrocarbons therefrom, debutanizing the said fractionated stream to separate at least a portion of the normal butane thereby increasing the concentration of isobutane and butylenes therein, continuously injecting said debutanized product in a circulating stream of emulsion of hydrocarbons and liquid alkylation catalyst in a closed circuit in an alkylation zone wherein isobutane is alkylated by the olefins with the production of gasoline hydrocarbons of high anti-knock value, withdrawing reaction products from the alkylation zone and separating unstabilized alkylate therefrom, stabilizing said separated alkylate to remove a light fraction consisting essentially of isobutane, normal butane and any C₃ hydrocarbons retained in the system, recycling a portion of said light fraction to the aforesaid stabilizer C₄ fractionating operation to prevent buildup of C₃ hydrocarbons in the system while retaining the excess isobutane therein, fractionating another portion of said light fraction to separate an isobutane-rich fraction from a normal butane fraction, and recycling at least a portion of the isobutane-rich fraction directly to the alkylation zone to maintain an excess of isobutane therein while preventing buildup of normal butane in the system.

6. A process for the manufacture of anti-knock gasoline which comprises stabilizing an unstabilized cracked naphtha, separating a C₄ hydrocarbon stream from the stabilizer containing butylenes, normal butane, isobutane and some C₃ hydrocarbons, fractionating said stream to remove C₃ hydrocarbons therefrom, debutanizing the said fractionated stream to separate at least a portion of the normal butane thereby increasing the concentration of isobutane and butylenes therein, splitting said debutanized product into a plurality of streams, separately and simultaneously passing each stream to separate stages of a multi-stage alkylation system comprising a plurality of serially connected alkylation zones through which the hydrocarbons undergoing treatment flow in series, and in each of which the hydrocarbons are subjected to contact with a liquid alkylation catalyst under conditions such that isobutane is alkylated by the butylenes to produce gasoline hydrocarbons of high anti-knock value, withdrawing reaction products from the final stage of the system and separating unstabilized alkylate therefrom, stabilizing said separated alkylate to remove a light fraction consisting essentially of isobutane, normal butane and any C₃ hydrocarbons retained in the system, recycling a portion of said light fraction to the aforesaid stabilizer C₄ fractionating operation to prevent buildup of C₃ hydrocarbons in the system while retaining the excess isobutane therein, separately fractionating another portion of said light fraction to remove an isobutane-rich fraction from a normal butane fraction, and recycling at

least a portion of the isobutane-rich fraction directly to the first stage of said alkylation system, whereby an excess of isobutane is maintained in said system and flows serially therethrough while buildup of normal butane in the system is prevented.

7. In the alkylation of isobutane with butylenes of a normally gaseous hydrocarbon fraction of cracking still gases in the presence of an alkylation catalyst for the production of gasoline hydrocarbons of high anti-knock value, the method which comprises fractionating the said cracking still gases to remove C₃ and lighter hydrocarbons therefrom, and also to remove at least a portion of the normal butane to provide a C₄ fraction concentrated in isobutane and butylenes, subjecting the said C₄ fraction to alkylation with excess isobutane in the presence of an alkylation catalyst under conditions such that isobutane is alkylated by the butylenes to produce gasoline hydrocarbons of high anti-knock value, separating unstabilized alkylate from the reaction products, stabilizing said separated alkylate to remove a normally gaseous fraction consisting essentially of isobutane and normal butane with any C₃ hydrocarbons retained in the system, and recycling at least a portion of said normally gaseous fraction to the first-mentioned fractionating operation of the cracking still gases to thereby prevent buildup of C₃ hydrocarbons and normal butane in the system while maintaining excess isobutane therein.

8. The method according to claim 7, wherein the said normally gaseous fraction removed in the stabilization of the alkylate is divided into streams, one stream being recycled to the said fractionating operation of the cracking still gases, and another stream being separately fractionated to remove an isobutane-rich fraction from a normal butane fraction, and the said isobutane-rich fraction is recycled directly to the alkylation operation.

9. In the alkylation of isobutane with butylenes of a normally gaseous hydrocarbon fraction of cracking still gases containing C₃ and C₄ hydrocarbons including propane, isobutane, normal butane and butylenes in the presence of an alkylation catalyst for the production of gasoline hydrocarbons of high anti-knock value, the method of handling the said fraction of cracking still gases without the addition of extraneous large amounts of isobutane which comprises fractionating the said cracking still gases to separate C₃ hydrocarbons and also to separate a substantial proportion of the normal butane therefrom to thereby obtain a C₄ hydrocarbon fraction concentrated in isobutane and butylenes and containing only a relatively small proportion of normal butane, the isobutane content of said fraction being in molar excess of the total olefin content thereof, subjecting the said C₄ fraction to alkylation in the presence of an alkylation catalyst under conditions such that isobutane is alkylated by the butylenes to produce gasoline hydrocarbons of high anti-knock value, separating an unstabilized alkylate from the reaction products, stabilizing said separated alkylate to remove a normally gaseous fraction consisting essentially of normal butane and the excess isobutane together with any C₃ hydrocarbons retained in the system, and recycling at least a portion of the said normally gaseous fraction to the first-mentioned fractionating operation of the cracking still gases to thereby prevent buildup of C₃ hydrocarbons and normal butane in the

system while maintaining excess isobutane therein.

10. The method according to claim 9, wherein the said normally gaseous fraction separated in the stabilization of the alkylate is divided into streams, one stream being recycled to the said cracking still gas fractionating operation, and another stream being separately fractionated to remove an isobutane-rich fraction from a normal butane fraction, with the said isobutane-rich fraction being recycled directly to the alkylation operation.

11. In the alkylation of isobutane with butylenes in the presence of an alkylation catalyst in a multi-stage system involving serial flow through a plurality of alkylation zones for the production of gasoline hydrocarbons of high anti-knock value, and wherein a C₃—C₄ hydrocarbon fraction of cracking still gases containing propane, isobutane, butylenes and normal butane is employed as a charge stock, the method which comprises fractionating the said C₃—C₄ hydrocarbon fraction to remove C₃ hydrocarbons and also to remove a substantial proportion of the normal butane therefrom to provide a C₄ hydrocarbon fraction concentrated in isobutane and butylenes, with the isobutane in molar excess of the butylenes, separately and simultaneously introducing portions of the said C₄ fraction into at least two stages of the said multi-stage alkylation system whereby isobutane is alkylated by butylenes in each of said stages to produce gasoline hydrocarbons of high anti-knock value and gasoline hydrocarbons together with excess isobutane flow serially from a preceding stage to a succeeding stage of said system, separating an unstabilized alkylate from the reaction products of a final stage of said system, stabilizing said separated alkylate to remove a normally gaseous fraction consisting essentially of normal butane and excess isobutane, fractionating at least a portion of said normally gaseous fraction to separate an isobutane-rich fraction from a normal butane fraction, returning another portion of said normal gaseous fraction to the said C₃—C₄ hydrocarbon fractionating step, recycling the isobutane-rich fraction directly to the first stage of the alkylation system to thereby provide a substantial excess of isobutane which flows serially through the multiple stages of said system, and 50

discharging the normal butane fraction to remove normal butane from the system in an amount comparable to the amount of normal butane introduced with the C₄ hydrocarbon feed into the alkylation system.

12. A continuous multi-stage process for alkylating a low-boiling isoparaffin with an olefin in the presence of an immiscible liquid alkylation catalyst to produce gasoline hydrocarbons of high 10 anti-knock value, which comprises maintaining in each stage of said multi-stage system a recirculating liquid emulsion stream of catalyst, hydrocarbon reaction products and excess isoparaffin in a closed circuit including a restricted 15 flow passage and an enlarged reaction zone, splitting the olefin feed between at least two of said stages by simultaneously introducing the olefin in liquid phase and in controlled amounts into the restricted flow passage of each of said stages 20 under conditions such that the isoparaffin is maintained in substantial molar excess in each of said stages and isoparaffin is alkylated with the olefin to produce gasoline hydrocarbons of high anti-knock value as the emulsion stream 25 circulates through the restricted flow passage and enlarged reaction zone, continuously removing a small portion of the recirculating emulsion stream from each stage, passing hydrocarbon reaction products and excess isoparaffin of the removed 30 stream from a prior stage and introducing the same into the recirculating emulsion stream of a subsequent stage whereby the hydrocarbon reaction products and excess isoparaffin flow serially through said stages, continuously separating 35 excess isoparaffin from hydrocarbon reaction products removed from the final stage, dividing said excess isoparaffin separated from hydrocarbon reaction products, recycling one portion of said excess isoparaffin to the recirculating emulsion stream of the first-mentioned stage to thereby assist in maintaining the said substantial molar excess of isoparaffin in said stages, and 40 adding another portion of said separated excess isoparaffin to the olefin feed which is then fractionated to remove propane and ultimately split 45 between said stages.
